United States Patent Office.

VICTOR KELLER, OF ALLEGHENY, PENNSYLVANIA.

Letters Patent No. 98,777, dated January 11, 1870.

IMPROVEMENT IN ENAMELLING OVENS.

The Schedule referred to in these Letters Patent and making part of the same.

To all whom it may concern:

Be it known that I, VICTOR KELLER, of the city and county of Allegheny, and State of Pennsylvania, have invented a new and useful Improvement in Enamelling Ovens; and I do hereby declare that the following is a full, clear, and exact description thereof, reference being had to the accompanying drawings, and to the letters of reference marked thereon.

The nature of my invention consists in constructing an enamelling-oven, so that the heat will be equally distributed over the bottom and around the muffler or crown of the oven, also in providing the oven with operating-gear, so arranged, with relation to the oven, as to automatically open and close its doors, and convey into and out of it the articles to be dried, baked, or enamelled.

To enable others skilled in the art to make and use my invention, I will proceed to describe its construction and operation.

In the accompanying drawings, which form part of my specification—

Figure 1, Sheet A, is a side and front elevation of my improvement in enamelling-ovens.

Figure 2 is a side and back elevation of the same.

Figure 3, Sheet B, is a longitudinal section of the same.

Figure 4 is an end view of the same.

Figure 5 is a transverse section of the oven when cut through at line *y* of fig. 1.

Figure 6 is a transverse section of the oven, representing the upper part of it removed, as indicated at line *y'* of fig. 5.

In the accompanying drawings—

A represents the walls of the oven.

B represents the fire-chambers, which are provided each with a flue, 1, 2, and 3, from which radiates a series of flues, as shown at 5 in fig. 6, Sheet B. These flues 5 connect with the flue 4, which surrounds the muffler or crown *Z* of the oven *A'*.

From the flue 4, lead three flues, as indicated at 6, and are arranged, so that they are on a vertical line with the flues 1, 2, and 3, leading from the fire-chambers *B*, and are connected by flues 10 with the flue *x*, which is connected to a suitable chimney or stack.

The bottom 11 of the oven is formed of tiles made of fire-clay, or other refractory material, and the muffler or crown *Z* of the oven may be formed of tile, brick, or iron, and may be made in one or more pieces, as indicated at 12 in fig. 3 of Sheet B.

At each end of the oven *A'* are arranged frames *C*, which support the gearing which is used for operating the endless aprons *P P*, and opening and closing the doors 8 of the oven *A'*.

On the bottom 11 of the oven are two iron bars, *R*, which are held together by cross-bars. These bars *R*

are used as guides, upon which the endless aprons *P* travel, and hold the aprons up off the bottom 11, for the purpose of preventing them from causing any dust to arise in the oven in their passage through it.

The endless aprons *P P* are arranged on pulleys *D*, *D'*, and *e*, and travel in opposite directions, and move through the oven at suitable intervals.

To the door 8 of the oven, are attached rods or chains *7*, which are connected to the inner ends of levers *m*, which are pivoted on the shafts of the pulleys *e*. To the outer ends of the levers are attached rods or chains *n*, the lower ends of which are attached to levers *w*, which are pivoted at 9.

The endless aprons *P P* and doors 8 are operated through the medium of the gearing marked *l o t s j k f g h i*, and cone-pulleys *B* and *C*, the construction and arrangement of which will be readily understood by the skilful mechanic.

The movements of the endless aprons and doors being dependent upon the driving or operating-gear, and as the movements of the endless aprons and doors of the oven must be adjusted to the kind of drying, baking, japanning, or enamelling to be done in the oven, therefore, I wish it clearly understood that I do not confine myself to any single arrangement of the gear, or to the size or form of the pulleys and wheels used.

As the construction and arrangement of the several parts of my improvement, and the relation that the several parts bear to each other, will be readily understood from the foregoing description, and by reference to the accompanying drawings, I will therefore proceed to describe the operation of my improvement; which is as follows:

In the process of enamelling the interior of iron-ware, I have found it to be of great advantage to use three ovens, constructed substantially as herein described, two of the ovens to be provided each with a single endless apron, and arranging the lever for opening the door at one end of the oven, as indicated by the dotted lines 13, so that the gearing at one end of the oven will open and close both doors at the desired time.

The levers *m* and *w* may be lengthened for obtaining greater leverage, as indicated by the dotted lines 14, thereby requiring less power to raise the doors. For enamelling iron, as stated, the three ovens should be arranged so as to be convenient for conveying the article to be enamelled from the ovens to the workmen, and from one oven to the other.

The two single ovens, I use for drying the coatings of the enamel on the ware, and the third one, which is the one herein described and represented, I use for baking the enamel on the ware. When the ware is coated with the enamelling-material, the vessels or articles are placed on one of the endless aprons *P*.

Now, by turning the crank f'' , it will revolve the wheels f and g , which will revolve the cone-pulley C' , which will, through the medium of a belt, revolve the cone-pulley B' , which will revolve the wheel h , which will revolve the wheel i , which will revolve the wheels l o , shaft 15, and wheels s and t , which will revolve the section of a wheel, J , which gears into the wheel f' . The revolving of the wheel i will also revolve the section of a wheel, J' , which gears into the wheel k , and the sections of wheels J J' will rotate the wheels f' and k in opposite directions, and cause the pulleys D and D' to revolve in like manner, and thereby cause the endless aprons to travel in opposite directions.

On the same shafts that carry the section of wheels J J' , are arranged cams u , which are so arranged, with relation to the sections of wheels J J' , that the cams will press down the levers w , which, through the medium of the rods or chains n and 7 , and the levers m , will raise the doors 8 of the oven A' , and as soon as the doors begin to rise, the sections of wheels J J' will commence to rotate the wheels f' and k , which will revolve the pulleys D and D' until one of the endless aprons has carried a vessel into the oven, and the other has carried a vessel out of the oven. The sections of wheels J J' will, by this time, become unshipped from the wheels f and k , and the motions of the aprons stopped, and the cams u will also become unshipped from the levers w , and thereby allow the doors 8 of the oven to close by their own gravity, and thus will the revolving of the gear continue to act, and cause the endless aprons to travel, and the doors of the oven to open and close at suitable intervals, suitable to the movements of the workmen for manipulating and enamelling the wares or articles to be dried, baked, japanned, or enamelled.

The heat from the fire-chambers B passes up through the flues 1, 2, and 3, and from them through the flues 5, and passes into flues 4, and up through them, around the muffler or crown of the oven, into the flues 6, and through them into flues 10 and x , and from flue x into the chimney or stack.

It will readily be seen and understood, that an oven constructed and provided with the operating-gear, as herein described, can be used for drying, baking crackers or bread, japanning tin or sheet-iron ware, as well as for enamelling iron-ware, by simply arranging the operating-gear so as to obtain that motion of the parts which is best adapted to the works required of the oven.

Having thus described the nature, construction, arrangement, and operation of my improvement in enamelling-ovens,

What I claim as of my invention, is—

1. The arrangement of the flues 1, 2, 3, 5, 4, 6, all concentrating in flue x , and arranged and combined, with relation to the oven A' , substantially as herein described, and for the purpose set forth.
2. Constructing the muffler or crown Z of the oven in two or more pieces, with lap-joints, as indicated at 12, substantially as herein described.
3. Causing the endless aprons P P to travel, and the oven-doors 8 automatically to open and close at suitable intervals, by means of suitable operating-gear, substantially as herein described, and for the purpose set forth.

VICTOR KELLER.
